BEAM TYPE ELECTRON DISCHARGE DEVICE

Bernard C. Gardner, Redwood City, Calif., assignor to Raytheon Manufacturing Company, Newton, Mass., a corporation of Delaware

Application April 18, 1950, Serial No. 156,660

9 Claims. (CL 313—72)

1

This invention relates to electron discharge devices, and more particularly to an amplifier of the deflection modulation type which may be used as an analogue computer.

Cathode ray tubes can be used as analogue computers by placing a target in the path of the electron stream and masking said target with the shield having a particular configuration such that the beam impinges partially on the mask and partially on the target electrode. By then deflecting the beam, the number of electrons striking the target electrode may be varied in accordance with any desired function of the input deflection voltage by the use of a particular contour of masking electrode. For example, a beam may be emitted from a cathode ray tube gun in the form of a triangular plane with the apex of the plane at the gun and the base of the plane a vertical line of impingement of electrons on the target or masking electrodes. If the electron beam is then moved horizontally such that the position of the line of impingement of the beam on the masking electrode changes, the contour of the edge of the masking electrode will determine the number of electrons striking the target electrode.

It has been found that certain inaccuracies are inherent in this device, since the ends of the line of impingement of the beam would not have a density which is uniform with respect to the density of the impingement line at the center thereof. Therefore, it becomes impossible to compute exactly the shape of the curve of the masking electrode. Since the accuracy of the device depends upon the accuracy to which the curve of the masking electrode is computed, and, since adjustment of this curve is impossible following assembly of the device, it has been found to be impossible to construct this type of computer with large degrees of accuracy.

This invention discloses a beam deflection device wherein the edge effects of the beam are eliminated, and hence the curve of the masking electrode may be computed with a high degree of accuracy.

Briefly, the invention embodies the use of an electron beam in the form of a disk, the electrons of said beam emanating from a cathode at the center of said disk. The periphery of said disk impinges upon an apertured, cylindrical masking electrode behind which is positioned a target or collecting electrode. Disk-shaped deflection plates are positioned substantially parallel to the electron beam disk such that the

2

voltages applied between the deflection plates cause the disk to be deformed into a conical beam so that either more or less electrons impinge upon the masking electrode, the number of electrons impinging upon the masking electrode being controlled by the size and shape of apertures therein.

In addition, since the total current of the beam is limited by the area of impingement of the electrons on the anode structure and the resultant heating thereof, the radial or disk type beam allows a much higher current than a linear type beam with the resultant higher signal level. Also, the radial type device disclosed herein may be made considerably more compact than a linear type device, being, for example, two or three inches in diameter and two or three inches in length as against a similar diameter and ten to twelve inches in length for a linear type structure.

Other and further advantages of this invention will become more apparent as the description thereof progresses, reference being had to the accompanying drawing, wherein:

Fig. 1 illustrates a longitudinal, cross-sectional view of an electron discharge device embodying this invention taken along line 1—1 of Fig. 2;

Fig. 2 illustrates a transverse, cross-sectional view of the device shown in Fig. 1 taken along line 2—2 of Fig. 1; and

Fig. 3 illustrates a circuit utilizing the device of Figs. 1 and 2.

Referring now to Figs. 1 and 2, there is shown an evacuated envelope 10 which may be made, for example, of glass having positioned therein a cathode 11 coaxial with envelope 10. Cathode 11 comprises a cathode cylinder 12 which may be of any desired conductive material such as, for example, tungsten. Inside cylinder 12 is a heating element comprising a coil 13, one end of which is attached to the cylinder 12 and the other end of which extends down through the bottom end of cylinder 12 and is connected to a lead-in member 14 which passes through a glass seal in the base of envelope 10. The cathode cylinder 12 is supported by a similar lead-in member 15 which passes through a glass seal in the base of envelope 10. A portion of the outer surface of cylinder 12 is coated with electron emissive material 17 such that, when a suitable heater voltage is applied between leads 14 and 15, cylinder 12 will be raised to a sufficient temperature for coating 17 to emit electrons.

Surrounding the portion of cylinder 12 which is coated with electron emissive material and

coaxial therewith is a masking electrode 18 which is cylindrical in form and has a plurality of apertures therein. Masking electrode 18 is supported by a plurality of lead-in members 19 which pass through the bottom of envelope 10 and are sealed therein. Surrounding masking electrode 18 and coaxial therewith is a collecting electrode 20 which is cylindrical in form and is supported by a plurality of lead-in members 21 which are sealed through the bottom of envelope 10.

Positioned above cathode 11 is a metallic disk 22 which is supported by a lead-in member 23 sealed through the top of envelope 10. Disk 22 operates as a deflection plate and is positioned slightly above the upper end of masking electrode 18 and is somewhat smaller in diameter than masking electrode 18. Positioned below masking electrode 18 is a second deflection plate 24 which comprises a flat, annular metallic member supported by lead-in members 25 sealed through the bottom of envelope 10. Member 24 has an outside diameter which is equal to the diameter of member 22 and has a hole 26 in the center thereof to allow the passage of the cathode 11 therethrough.

Referring now to Fig. 3, there is illustrated a mode of operation of the device of Figs. 1 and 2. The heater coil 13 has a voltage applied thereacross by means of a battery 27. Cathode 11 is attached to a variable tap 28 of a battery 29 which may have a total overall value of, for example, a few hundred volts. The negative end of battery 29 is connected through input load resistors 30 and 31 to lower and upper deflection plates 24 and 22, respectively. An input signal amplifier has its output connected across electrodes 22 and 24, whereby a signal is impressed therebetween. Masking electrode 18 is connected to a tap 32 on battery 29 which is considerably more positive than variable tap 28. Collecting electrode 20 is connected through an output load resistor 33 through the positive end of battery 29. The electron beam is attracted to masking electrode 18 and collecting electrode 20 due to the positive potentials between the cathode 11 and said electrodes. By adjustment of variable tap 28, the negative bias on the deflection electrodes 22 and 24 may be adjusted such that the point of impingement of the electron beam on the masking electrode 18 is a sharp, circular line. If desired, other electrodes may be used in the structure to facilitate focusing and to control the intensity of the electron beam.

When a voltage is applied between electrodes 22 and 24 by a signal from a signal input amplifier 34, the beam will be moved either up or down at the point of impingement of said beam on masking electrode 18 dependent on the instantaneous polarity of the input signal. Due to the non-uniform shape of the apertures in the masking electrode 18, movement of the point of impingement of said beam on masking electrode 18 varies the current which passes through said apertures to the collecting electrode 20, thereby varying the voltage developed across load resistor 33. The voltage developed across resistor 33 is fed to an output signal amplifier 35 to be used for any desired purpose. By varying the shape of the apertures in masking electrode 18, the output signal developed across resistor 33 may be made to have any desired functional relationship to the input signal applied to plates 22 and 24. In effect, the output signal represents the solution of a particular problem according

to a particular formula and, therefore, the system may be termed an analogue computer.

If desired, the output electrode may be made in a plurality of sections, each section covering 5 one or a plurality of apertures in the masking electrode 18. Each output section may be fed to a different output, and the apertures in front of the various output sections may have different shapes, whereby a plurality of different functions 10 may be computed simultaneously. Due to the fact that the beam is radial, it has no end points in a direction perpendicular to the deflecting direction, and hence the inaccuracies 15 which are encountered in linear beams are eliminated.

This completes the description of the particular embodiment of the invention illustrated herein. However, many modifications thereof 20 will be apparent to persons skilled in the art. For example, the signal could be taken from the masking electrode rather than the collecting electrode, if desired. Other types of cathodes could be used, and any desired shape or size of aperture could be used in the masking electrode 25 18 without departing from the spirit and scope of this invention. Therefore, applicant does not wish to be limited to the particular details of the embodiment of the invention illustrated herein, except as defined by the appended claims.

30 What is claimed is:

1. An electron discharge device comprising an electron source, means for forming electrons from said source into a conical beam, a target electrode, and means for varying the conical angle of said beam prior to impingement of said beam on said target electrode to thereby vary the number of electrons impinging on said target electrode, the percentage of said beam which impinges on said target electrode varying 35 as a continuous function of said conical angle.

2. An electron discharge device comprising an electron source, means for forming electrons from said source into a conical beam, a masking electrode having non-linear discontinuities 45 therein upon which a portion of said beam will impinge, a collecting electrode, and means for varying the conical angle of said beam prior to impingement of said beam on said masking electrode to thereby vary the number of electrons impinging on said masking electrode.

3. An electron discharge device comprising an electron source, means for forming electrons from said source into a conical beam, a masking electrode having an aperture therein, said aperture having a non-linear contour, a collecting electrode positioned outside said masking electrode, and means for varying the conical angle of said beam prior to impingement of said beam on said masking electrode.

60 4. An electron discharge device comprising an electron source, means for forming electrons from said source into a conical beam, a masking electrode upon which a portion of said beam will impinge comprising an apertured cylinder surrounding said source, a collecting electrode positioned outside said masking electrode coaxial with said source, the apertures of said cylinder having sides which are non-linear in a direction parallel to the axis of said beam, and means for varying the conical angle of said beam prior to impingement of said beam on said masking electrode.

65 5. A computer comprising an electron discharge device having signal input means and signal output means for producing a signal out- 70 75

put bearing a non-linear continuous functional relation to a signal supplied to said input means, said discharge device comprising an electron source, means for forming electrons from said source into a conical beam, a target electrode which is non-uniform with respect to said beam, and means prior to said impingement of said beam on said target electrode for varying the conical angle of said beam.

6. A computer comprising an electron discharge device having signal input means and signal output means for producing a signal output bearing a non-linear continuous functional relation to a signal supplied to said input means, said discharge device comprising an electron source, means for forming electrons from said source into a conical beam, a masking electrode upon which a portion of said beam will impinge, a collecting electrode positioned outside said masking electrode, and means prior to the impingement of said beam on said masking electrode for deflecting said beam substantially transversely to the direction of motion of said beam.

7. An electron discharge device comprising a source of electrons adapted to produce a conical electron beam, an electrode positioned in the path of said beam, said electrode having a discontinuity therein which varies as a continuous function of the conical angle of said beam, and a beam deflection element intermediate said source and said electrode to vary the conical angle of said beam.

8. An electron discharge device comprising a source of electrons adapted to produce a conical electron beam, an electrode positioned in the path of said beam, said electrode having an aperture therein which varies as a continuous function of the conical angle of said beam, and a beam deflection element intermediate said source and said electrode adapted to vary the conical angle of said beam.

9. An electron discharge device comprising a source of electrons adapted to produce a conical electron beam, an electrode positioned in the path of said beam, said electrode having a discontinuity therein which varies as a continuous function of the conical angle of said beam, a beam deflection element intermediate said source and said electrode adapted to vary the conical angle of said beam, and a target positioned in the path of said beam on the opposite side of said electrode from said source.
